BINDING POST

Stephen N. Buchanan, Washington, D. C.

Application June 11, 1940, Serial No. 339,967

3 Claims. (Cl. 173—259)

This invention relates to binding posts and the like. Among the purposes of the invention is to provide improved anchoring means for such devices. Another purpose is to provide a construction enabling a wire or wires to be efficiently gripped, and wherein the parts cannot become separated in use. A practical embodiment of the invention is shown in the accompanying drawing, by way of example, and the description will proceed with reference to the drawing, in which—

Figure 1 is a partial section of a base plate showing the new binding post in elevation;

Figure 2 is a section on line 2—2 of Figure 1;

Figure 3 is a section on line 3—3 of Figure 1;

Figure 4 is a section on line 4—4 of Figure 2;

and

Figure 5 shows a modification.

Referring to the drawing and first to Figures 1 to 4, reference numeral 10 designates an anchor member in the form of a cup having a threaded opening or socket 11 and an annular bottom flange 12 defining a circular aperture 13. The anchor member is externally knurled and is moulded in the top portion of a base plate 14 of Bakelite or the like, as here shown. The base plate has a circular bottom opening 15 which registers with the opening 13 of the anchor member.

A post 16, which is externally threaded throughout, is provided with a diametrical slot 17 extending from its lower end and terminating short of its upper end. The lower slotted end of the post is threaded in the opening or socket 11 and ordinarily against the flange 12 which serves as a stop. The lower end of the post is internally threaded and receives the end of a screw 18 passed upwardly through the openings 15 and 13, the screw having a head engaging the bottom of the base plate 14. With the screw 18 engaged with the post, as particularly shown in Figure 2, the post is securely held in the anchor member and its lower end is supported by the screw against collapse. As a preferred feature, assuming the post to have a right-hand thread, the screw 18 has a left-hand thread. Consequently, with the lower end of the post threaded against the stop 12 and the screw 18 tightened in position, the post can be turned in neither direction.

Strung slidably on the lower end of the post is a washer 19 which has a diametrical bar portion 20 in the slot 17. Above the washer 19 a nut 21 is threaded on the post. A clip 22 comprises a bridge portion 23 extending freely

through slot 17 and indent end portions 24 and 25 engaged in an annular groove 26 formed in a lower circular boss 27 of the nut. The end edges 24 and 25 are arcuate, as particularly shown in Figure 3, and embrace the groove bottom in such manner that the clip and nut are held together even previous to assembly on the post. The bridge portion 23 is longitudinally channelled to provide a groove 23'.

It will be evident that a wire or wires inserted through slot 17 between washer 19 and bridge piece 23 will be firmly clamped between these members when nut 21 is threaded downwardly. The bar portion 20 of washer 19 serves as an abutment against which the wire or wires are pressed by the bridge portion 23, the wire engaged by the bridge portion being centered relative to the latter by the groove 23'. In the case of several wires to be connected, it will of course be understood that additional washers 19 may be provided if desired. Movement of the nut off of the top post is prevented by the engagement of the bridge piece with the top wall of slot 17.

In Figure 5, reference numeral 28 designates a metal strip constituting an extension secured to a bus bar 29. The free end of the extension is provided with a cup portion 30, constituting an anchor member, which is internally threaded and provided with a bottom flange exactly as in the case of the member 10, the portion 30 receiving the lower end of the post 16 and the somewhat shorter screw 18' in the same manner and with the same effect as hereinbefore described.

It will be evident that the invention is susceptible of varied embodiment as to details of form and arrangement, and accordingly I do not limit myself in these respects except as in the following claims:

I claim:

1. A device of the class described comprising an anchor member having an opening, an externally threaded post having a diametrical slot extending from one end of the post and terminating short of the other end of the latter, the slotted end of the post being received in said opening and being provided with internal threads, a screw engaged with said internal threads of said post and securing the post in said opening, and a nut on the external threads of said post.

2. A device of the class described comprising an anchor member having a threaded opening,

an externally threaded post having a diametrical slot extending from one end of the post and terminating short of the other end of the latter, the slotted end of the post being threaded in said opening and being provided with internal threads, a screw engaged with said internal threads of said post and securing the post in

said opening, and a nut on the external threads of said post.

3. The combination according to claim 2 wherein of the external and internal threads of the post, one is right-hand and the other left-hand.

STEPHEN N. BUCHANAN.
